VARIABLE ANTENNA

Nicholas C. Amen, Glendale, Calif.

Application May 28, 1951, Serial No. 228,653

8 Claims. (Cl. 250—33.65)

1

This invention relates to antennas in general, but it is especially adapted to receiving antennas for television programs. Present day antennas are not satisfactory in that their lengths are fixed and are not adjustable for perfect or near perfect wave length reception. Present day antenna reflectors are not adjustable either and therefore cannot provide efficient power buildup nor effective shielding performance. Furthermore, so far as known, antennas now in use are not rotatable and cannot be turned for purposes of directivity so as to take advantage of clear-shot reception or be set in correct position for bias reception waves when the short waves are deflected by hazards upon the earth's surface which may be magnetic or just physical impediments such as mountains, buildings etc.

Television requires a wide bandwidth for the reason that a great deal of intelligence must be transmitted per unit of time. Such a necessary condition is vexed with a variety of interferences which may cause ghost signals, picture shimmying and shading effects which can and do mar television reception and irk the tele-audiences. It is believed that this invention will remedy most of these well known faults, if not all of them, and thus be a means for presenting better television of greater interest.

The most important object of this invention is to provide better television reception through the employment of a simple, durable and compact structural device that is not very expensive to make and manufacture, but a device which is efficient in use and service and one that is most effective for the purposes intended.

Other objects, advantages and features of this invention will be more apparent upon careful perusal of the accompanying drawings, the subjoined and detailed description, the preamble to this specification and the claims appended here-to.

Below, applicant describes one of the preferable forms of his invention, but it is to be understood that the drawings and description are not to limit the invention in any sense whatsoever except as the same may be limited by the prior pertinent art.

In the drawings:

Figure 1 is an elevational view, parts in section and parts broken away, showing an antenna device that is adjustable in wave length, adjustable in direction finding, and equipped with an adjustable reflector;

Figure 2 is a plan view of that shown in Fig. 1; 55 in either direction and that this can turn the

2

Figure 3 is an end elevational view of that shown in Figs. 1 and 2;

Figure 4 is an elevational view of a portion of the reflector;

5 Figure 5 is an enlarged elevational view of a spool-pulley unit;

Figure 6 is a plan view of that shown in Fig. 5;

10 Figure 7 is a vertical sectional view of a portion of the invention showing how the antenna frame is mounted upon a standard.

The particular form of the invention illustrated in the drawings, is shown as mounted upon a structural slab 1 which may be the roof of a building, but it is to be understood that any suitable and convenient means may be employed for supporting the antenna above ground to the desired height. A flanged tubing 2 is employed as a standard for the antenna frame 5 and the flange 3 of the standard is rested upon or secured to the slab 1. When required, an extended tube or rod portion or stud means 4 at the top center of the frame 5 may be employed for attachment of guy wires and the like so as to give the antenna sturdiness and firmness. Such a stud means is provided with a swivel joint so that the antenna frame 5 can be turned in various directions.

15 The frame 5 has the elongated bottom member 6 which is spaced from a similar top member 7, the two members being rigidly positioned by the upright side members 8 and 9. This entire frame may be an integral piece of light metal or plastic material or the frame may be fabricated from single pieces and the ends of them suitably joined together. The bottom member 6 is secured to the top of a ball bearing race head 10 by bolts or other suitable means and this head is supported by the top end of the standard 2 40 by the plurality of ball bearings 12.

45 The frame member 6 has a bore 13 which accommodates a rod or tube 14 of insulating or non-insulating material, and this rod terminates in a flanged member 15 which is firmly secured to the bottom surface of the top frame member 7, as shown. The race head 10 has a depending flange 16 which is a spacer between the standard 2 and a tubular shaft member 17, the top end of this shaft member being secured to the inner surface of the race head flange 16 by suitable means which may be spot welding in the event these structural members be of metal; thus it can be seen that the tubular shaft 17 can be turned 50 in either direction and that this can turn the

race head 16 as well as the frame 5 for directivity purposes.

The bottom end of the tube 17 is provided with a bevelled gear 18 which is keyed thereto and which is in mesh with a similar bevelled gear 19 that is keyed to a control rod 20. This control rod leads to some remote suitable place and is provided with some crank means (not shown) for turning it. The bottom end of the rod or tube 14 is also provided with a bevelled gear indicated at 21 which is in mesh with a similar gear 22 that is keyed to a rod 23, this rod having at its remote end, not shown, some means for turning it such as a crank, for instance.

At one end of the antenna frame there is journalled a rod 24 upon which there is a plurality of pulley wheels 25 anchored thereto in predetermined spaced relationship. A similar rod 26 is journalled at the other end of the frame and this rod also has a plurality of pulley wheels indicated by 27 anchored thereto. The center mast or tube 14 has a plurality of spool-pulley units 28 keyed thereto in spaced relationship so as to be in alignment with the pulley wheels 25 and 27.

Each spool-pulley unit consists of a spool or drum element 29, see Fig. 5, which is integral with or attached to a pulley wheel 30 so that these parts turn together and with the shaft or rod 14. On opposite sides of the spool are fixed the ends of a pair of antenna ribbons or bands 31 and 32 and the distal ends of these bands each have a coiled spring 33 attached thereto, one end of the spring being attached to the ribbon and the other end attached to one end of an insulator element 34. The other end of the insulator is attached to a guide wire 35 which passes around its respective pulley wheel 25 and the other end of which is fixed to the pulley 30 as by screw or any other suitable means. There is a plurality of these ribbons as indicated by the reference characters 31 to 44 incl. and they all are similarly constructed and arranged so that when the mast or control rod 14 is turned, all the conductor ribbons are wound or unwound in unison upon their respective spools 28. The springs 33 operate to keep the conductor ribbons taut at all times. Note, that the ribbons wind on their respective spools in the same direction as well as the wires upon their respective pulley wheels 30, for instance; each spool winds its pair of ribbons one within the other, and this forms interwound pairs of convolutes. In this manner, the ribbons, or dipoles, of each spool are shortened or lengthened at will so as to exactly match electrically, and to the particular wave band or channel desired. These ribbons may be of any material that is a good electrical conductor such as copper, aluminum, or other metals with or without a non-corrosive plating or cover.

The antenna means just described is provided with a reflector unit, screen or shield 45 to one side of the antenna 5 and the reflector is spaced one-half, one-quarter, or some other predetermined wave length from the antenna when they are in parallel registration as shown in Figs. 2 and 3 most clearly. The reflector consists of a rectangular frame having the bottom member 46, top member 47, and side upright members 48 and 49. This frame may be a single unitary integral structure or one fabricated from individual members which have their ends secured together in any suitable manner. The bottom member 46 has an offset portion 50 so as to accommodate certain structural parts and a gear. The frame supports a plurality of horizontal con-

ductor wires or reflector type conductors 51, these wires being held taut between the end insulator rods 52 and 53 which are slightly spaced from the frame members 48 and 49, respectively. 5 These wires 51 are preferably alined with the ribbons of the antenna proper so as to have parallel reflective qualities. All the reflector wires 51 are connected to a non-pick-up lead-in 50.

The offset portion of the reflector frame is 10 bridged by the structural rod or strut 54 which has bearing connection with a fixed bracket member 55 that is firmly secured to one side portion of the standard 2. Keyed to the rod 54 there is a worm wheel 56 that is operated by a 15 worm 57 that in turn is rotated or turned by a rod 58 that leads to some remote place where a crank may be provided (not shown) for turning the rod; and in this way the reflector may be placed in various inclined positions with respect to the antenna proper. A bracket 59 with a sleeve 58' extends from the standard 2 to which it is firmly attached, and the sleeve is a support bearing means for the worm 57. Obviously, chain and sprocket means as well as cable 20 and pulley means may be substituted for the worm wheel, worm and their rods for operational purposes.

A non-pick-up lead wire or cable 14' is provided within the pipe 14 for conducting signals to 30 a television set (not shown). Well known switches may be provided so that the lead-in wire of cable 50 of the reflector can be electrically connected to the lead-in from the antenna if desired.

35 In order to maintain the ribbons 31 to 44 clean and thus reduce electrical resistance and/or wave resistance, a pair of brushes is provided for each conductor ribbon and indicated by the numerals 60 and 61. These brushes are supported by 40 bracket means 62 and 63 and the bracket means 66 and 67, as shown. The brushes 60 and 61 constitute a pair and the brushes 64 and 65 constitute the other pair of each spool-pulley unit. The brackets 62 and 66 are supported by a common free riding bearing sleeve 68 and the other two brackets are supported by the common free 45 riding bearing sleeve 66. By this means, the conductor ribbons are kept clean and thus operate at a higher efficiency in receiving weak waves.

It is, of course, understood that various changes, substitutions and modifications may be made in the details of form, style, design, material and construction of the whole or any part 55 of the specifically described embodiment of this invention without departing from the spirit thereof; such possible changes and modifications are considered as being within the scope of the following claims.

60 I claim:

1. In an antenna device having a standard with means supporting a frame having materially spaced apart lateral uprights, a journalled mast extending upwardly from the standard and along a line intermediate the uprights and substantially parallel therewith, a spool and pulley unit fixed to the mast, a pair of flexible conductor ribbons having their proximate ends fixed to the spool and their other ends directed 65 in opposite directions toward their respective uprights, a rod parallel to and supported near each upright, a pulley wheel on each rod, a cable fixed to the distal end of one conductor ribbon and extending around its respective pulley wheel 70 in opposite directions toward their respective uprights, a rod parallel to and supported near each upright, a pulley wheel on each rod, a cable fixed to the distal end of one conductor ribbon and extending around its respective pulley wheel 75 and the other end of the cable fixed to said pulley

on the mast, another cable fixed to the distal end of the other conductor ribbon and extending around its respective pulley wheel and having its other end fixed to the pulley on the mast, and means for turning the mast so as to wind or unwind the conductor ribbons and cables to vary the wave lengths of the ribbons.

2. The antenna device recited in claim 1 wherein the standard is a hollow tube and the mast passes therethrough along with a shaft means for turning the frame of the antenna.

3. The antenna device recited in claim 1 wherein the conductor ribbons pass through a pair of cleaning brushes, and means extending from the mast for supporting the brushes.

4. The antenna device recited in claim 1 wherein a spring and insulator combination means is provided for each cable at the distal end of each conductor ribbon.

5. The antenna device recited in claim 1 wherein in a second frame for supporting reflector wires is pivoted to the standard, a plurality of reflector conductors fixed to the second frame, an offset portion in the bottom of the second frame and a worm wheel journaled therein, and a worm in mesh with the worm wheel for turning it and the second frame along a horizontal axis.

6. The antenna device recited in claim 1 wherein in a second frame is pivoted to the standard, a plurality of reflector wires supported by spaced insulating rods within the second frame, the second frame having a bottom member that is horizontally pivoted to the standard, and worm wheel and worm means for moving the second frame into various inclined positions with respect to the antenna frame.

7. An antenna device having a hollow standard extending from a supporting means, a journaled hollow shaft extending through the standard and having an antenna frame fixed to the

top thereof, a journaled mast rod extending through the shaft and frame and provided with a plurality of spaced apart spool-pulley units which are fixed to the mast rod, a journaled pulley rod means supported at one end of the frame and substantially parallel to the mast rod, a plurality of flexible conductor ribbons having one of their ends fixed to their respective spool and their distal ends fixed to cables which pass partly around the pulley rod means and which cables have their other ends fixed to their respective pulley of the spool pulley unit so that the lengths of the conductor ribbons can be changed by operation of the mast rod and the position of the frame can be changed by operation of the shaft.

8. The antenna device recited in claim 7 wherein the mentioned conductor ribbons and their associated parts are also provided on the opposite side of the mast rod, a reflector frame horizontally pivoted to the standard and arranged to be angularly displaced from the antenna frame and also into registration therewith, and a plurality of spaced apart conductors on the reflector frame positioned to be in parallel with the conductor ribbons when the frames are in registration.
